STOCKING

Philip Berusch, New York, N. Y., assignor to
Hoburt Hosiery Corporation, New York, N. Y.,
a corporation of New York

Application June 27, 1951, Serial No. 15,691

Term of patent 3½ years

(Cl. D47—7)

To all whom it may concern:

Be it known that I, Philip Berusch, a citizen of the United States, residing at New York, in the county and State of New York, have invented a new, original, and ornamental Design for a Stocking, of which the following is a specification, reference being had to the accompanying drawing, forming part thereof.

Fig. 1 is a side elevation of the stocking embodying my new design; and

Fig. 2 is a fragmental rear view thereof.

The dominant feature of the stocking design, prominently shown in Fig. 2, is an arrangement of two superimposed individual diamonds, the top one being smaller than the bottom one and both of the diamonds being surrounded by a frame extending to the lower heel portion, both the diamonds, the frame and the lower heel por-

tion being of a darker shade than the body of the stocking.

I claim:

The ornamental design for a stocking, substantially as shown and described.

PHILIP BERUSCH.
